UNITED STATES PATENT OFFICE.

ANGELO DE JULIAN, OF WEST PALM BEACH, FLORIDA.

ROOFING TILE.

1,414,774.

Specification of Letters Patent.

Patented May 2, 1922.

Application filed September 16, 1920. Serial No. 410,806.

To all whom it may concern:

Be it known that I, ANGELO DE JULIAN, a citizen of the United States, and a resident of West Palm Beach, in the county of Palm Beach and State of Florida, have invented certain new and useful Improvements in Roofing Tiles, of which the following is a specification.

My invention is an improvement in roofing tiles, and has for its object to provide a tile of the character specified, formed from plastic material as for instance cement, concrete or the like, wherein the tile is of such construction that it can be made in a variety of lengths and requires no special skill in laying.

In the drawings:

Figure 1 is a plan view of a portion of roof formed from the improved tiles,

Figures 2 and 3 are sections on the lines 2—2 and 3—3, respectively of Figure 1,

Figure 4 is a perspective view of one of the tiles, and

Figure 5 is a rear view.

In the present embodiment of the invention the improved tile which may be of any desired width and length is composed of cement and sand preferably, and each tile 1 is curved transversely as shown to form in the upper face of the tile a trough, leading from one end to the other. At one side edge each tile has a downwardly curved portion 2, and at the other side edge each tile has a trough or gutter 3 which is adapted to receive the downwardly bent portions 2 of the adjacent and succeeding tiles.

This gutter as clearly shown in Figure 1 is of greatest width at the top of the tile and gradually decreases in width toward the bottom, and the bottom of the trough is flat or plane. At its upper end each tile has an opening 4 in the central trough for receiving a nail or the like to secure the tile in place, and on its underface and near its lower end each tile has a transverse bar or lug 5, which is adapted to engage the upper end of the succeeding tile in the vertical course for limiting the lapping of the succeeding tile on the preceding.

Referring to Figure 1, it will be noticed that the tiles of each horizontal course are

laid with the downwardly curved portion 2 of the succeeding tiles in the gutters 3 of the preceding tiles. The next horizontal course is laid with the ends of the tiles of the course lapping on the tiles of the preceding course. Because of this lapping each trough 3 must receive at its upper end the lower end of the trough of the succeeding tile in the vertical course, as well as the lower end of the downwardly curved portion of the next tile in the succeeding course. Hence the gutters are made of greater width at their upper ends.

The nails which are driven through the openings 4 are hidden and covered by the lower ends of the succeeding course. The improved tiles can be made in a variety of lengths and they have nothing in their construction to limit their overlapping when set on the roof. No skill is required in the laying, and the curving transversely of the tile by means of which the outer edges of the tile are elevated, shields the joints between the tiles. The curve of the tile transversely provides between the trough at each side of each tile a rounded rib or ridge extending the full length of the tile and shielding the joint.

I claim:

1. A tile of plastic material having a body portion curved transversely and adapted to be laid with its concaved face upwardly, each tile having at one side edge a downwardly curved portion extending the full length of the side edge and having at the other side edge a longitudinally extending trough extending the full length of the said side edge, the tile having a transversely extending rib on its lower face and near its lower end for engaging the top of the adjacent tile in the preceding course.

2. A tile of plastic material having a body portion curved transversely and adapted to be laid with its concaved face upwardly, each tile having at one side edge a downwardly curved portion extending the full length of its side edge and having at its other side edge a tapered longitudinal trough having a flat bottom wall and extending the full length of the said side edge.

ANGELO DE JULIAN.
